ABSTRACT OF THE DISCLOSURE

System for precisely determining the gas content of a material using a levitation melting apparatus for extracting from a material sample the gas content of the sample including a closed melting chamber with an inert atmosphere in which only the sample under test is fused and no component within the chamber is heated to any appreciable temperature, whereby no extraneous gases are introduced.

BACKGROUND OF THE INVENTION**Field of the invention**

This invention relates to the art of extracting the gaseous content of a fusible sample and for analysis of the gas content of the sample without contamination or interference from extraneous gas sources. The apparatus comprises a specially constructed levitation melting system.

Description of the prior art

Materials such as metals may contain various gases adsorbed or dissolved therein, retained in intercrystalline spaces, or distributed molecularly or atomically therein, or by a combination of several of such mechanisms. Thus silicon steel may contain hydrogen, nitrogen, and oxygen as well as carbon monoxide and carbon dioxide. It is desirable to determine the content of these gases in the steel since the magnetic properties will vary markedly with some of these gases if in excess. For example, hydrogen gas has caused failure of large steel shafts when present in excess of certain critical proportions. In nuclear fuel and reactor structural elements, radioactive and by-product gases need to be determined accurately. Consequently, there is a need to detect and analyze for these gases in concentrations of less than one p.p.m.

A large number of analytical techniques are available for determining the concentration of gases in metals. These include hot extraction, Kjeldahl, combustion, vacuum fusion, spark source mass spectrometry, activation, isotopic dilution, and visual inspection. All of these methods have advantages and limitations dependent on such factors as sampled composition, sample shape and size, time required for analysis, detection limit, concentration range required, cost per analysis, cost of equipment, precision of results, etc. In the use of most of these techniques it is extremely difficult to obtain analysis of gases at concentrations of one part per million and less.

Levitation melting is a technique for melting a small amount of metal or other electrically conductive substance while it is magnetically suspended in a vacuum or in an inert gaseous atmosphere. The metal sample being melted is suspended within an electromagnetic field provided by an induction coil or the like with current of high frequency, such as about 450,000 hertz. The metal is heated by eddy current induced in it and is supported by repulsion between the induced eddy currents and the inducing coil current. The metal sample rapidly heats up and fuses as a result of these induced currents, with the metal being stirred by the electrical forces. An outstanding advantage of levitation melting is the removal of risk

2

of contamination of the sample by the exclusion of a contacting crucible or an electrode.

Levitation of a solid by means of an electromagnetic field has been known for some time. U.S. Patent Nos. 2,686,864 and 2,957,064 disclose devices for the levitation melting of metal samples, and are typical of the prior known devices for levitation melting. Such devices normally have enclosed a large part of the apparatus including the radio-frequency levitation coil within a bell jar or vacuum container in which the metal sample is levitated.

Many methods have been used to degas metals to some degree including levitation melting devices such as those disclosed in the above-mentioned patents. In those systems the field producing coils are contained within the vacuum, or inert atmosphere, in the bell jar or other confining means, the gases from the metal sample being melted are admixed with the gases released from the coils and other metal parts associated therewith. The heat radiated from the molten metal, and parts heated by induced currents causes gases to be released from any part subject to their influence. For example, in a larger system the initial pressure requirement in the bell jar for analyzing the gas content of a metal sample may be of the order of 10^{-9} torr while the gas released from the sample may raise the pressure to 10^{-8} torr; that is, 10% of the total gas from the system is background or contaminant gas which is not part of the sample.

Associated with the foregoing has been the problem of setting up the system for the analysis of only a single sample. Most of the prior known systems for the levitation melting of metals have involved a time-consuming procedure of placing the metal sample within the system, sealing the system, and then providing the proper atmosphere (vacuum or inert gas) within the system before the sample is melted.

In accordance with this invention, it has been found that the foregoing disadvantages may be overcome by providing a system in which the levitation coils are external of the melting zone in which the metal sample is disposed. Also, in the melting zone of the system a holder for a plurality of samples may be provided to enable the testing of any desired number of samples in a sequential manner, and thereby avoid the delay involved in setting up the system for all of the samples separately.

The advantage of the system of the present invention is that the out-gas effect of the system is reduced essentially to the sample and eliminates the out-gassing effect of other metal parts such as the induction heating coil which was formerly included in prior known levitation systems. Moreover, the smaller the system, the smaller the surface area of the surrounding that contributes to the out-gassing due to radiation heating from the heated sample.

Furthermore, in a smaller system a smaller sample may be used with the evacuated initial system pressure being of the order of 10^{-6} torr which is raised to a pressure of about 10^{-3} torr when the sample is levitation melted, with the background effect being only 0.1%. Thus, the sample pressure is raised by a factor of 1000 above the background gas content.

Accordingly, it is a general object of this invention to provide a metal levitation gas extraction system so proportioned and arranged, with an external levitating coil, so as to provide for rapid and accurate heating of a sample to the melting temperature whereby to extract all the gas and volatile content thereof, and to analyze the gas so extracted, without any substantial contamination by or inclusive of gases from portions of the system.

It is another object of this invention to provide a metal levitation gas extraction system to be employed with a gas analysis device which provides for the rapid heating and melting of a plurality of samples consecutively

and separately without requiring opening of the system.

It is another object of this invention to provide a metal levitation gas extraction system in which the potentially contaminating contributors are external of the melting zone.

Finally, it is an object of this invention to satisfy the foregoing objects and desiderata in a simple and expedient manner.

SUMMARY OF THE INVENTION

Briefly, the present invention consists of an elongated sealed container which communicates with a means for evacuating and analyzing the gases evolved in the container, and a levitation coil external of and surrounding the tubular container for creating an electromagnetic field for levitating, heating and melting a sample to be analyzed for its gas content within the container. The container is of such size and shape that no substantial amount of gas is evolved from any component other than the sample. The apparatus components are so arranged that no portion of the apparatus is subjected to sufficient heat to evolve any appreciable amount of gas within the container enclosure except the sample being analyzed. In addition, the device may include a holder for mounting a plurality of samples at vertically spaced intervals within the tubular container, and means for moving the tubular container or the heating coil longitudinally of the axis of the container to successively levitate and melt each sample within the container.

BRIEF DESCRIPTION OF THE DRAWING

For a better understanding of the nature and objects of this invention, reference is made to the drawings, in which similar numerals refer to similar parts in the several views of the drawings, and in which:

FIGURE 1 is an elevational view of the levitation gas extraction system of the present invention; and

FIG. 2 is an enlarged fragmentary view of the system showing the manner in which the metal sample is levitated within the tubular container.

DESCRIPTION OF THE PREFERRED EMBODIMENT

The device of the present invention is generally indicated at 10 in FIG. 1. It includes a tube 12, a conduit having rigid end portions 14 and 16 and an intermediate flexible portion 18, a joint 20 between the conduit portion 14 and the upper end of the tube 12, and a radio-frequency levitation coil 22.

The tube 12 is preferably circular in cross section and is an elongated member having a closed lower end 24. The upper end of the tube is open and communicates with the lower end of the conduit portion 14 to which connection is made by the joint 20 which is either a mechanical joint (O-ring or gold gasket) or involves a tapered fitted part as well as Apiezon wax for sealing the joint such as for a high vacuum condition.

The tube 12 is composed of a suitable high temperature material such as quartz, alumina, zirconia, or other high temperature oxides that can be fabricated into useful configuration. For lower temperature operations Pyrex glass may be used. The preferred material is quartz, because of its transparency as well as good high temperature and high vacuum properties. The conduit is heated by an electromagnetic field-inducing means such as by a field induced within the conduit by a radio-frequency coil 22.

As shown in FIG. 1, the end portions 14 and 16 of the conduit are provided with valves 26 and 28. The right end of the tube portion 16 (as viewed in FIG. 1) is connected to a mass spectrometer which is not shown in the drawing.

The intermediate portion 18 of the conduit is preferably composed of stainless steel. The intermediate portion is flexible to permit vertical movement of the tube 12 within the coil 22 as will be described hereinbelow.

As shown more particularly in FIG. 2, the coil 22 is a tubular member through which coolant such as water is passed during operation. The coil 22 preferably includes a lower portion 30 and an upper portion 32 which portions are interconnected by an intermediate portion 34. The coil 22 is preferably composed of a metal such as copper. The coil is powered by suitable means such as a 5 kw., 450 kc. generator.

Within the tube 12 means for supporting one or more samples to be levitated are provided and include an elongated rod 36 the lower end of which rests upon the lower end 24 of the tube 12. At spaced locations along the rod 36 a plurality of sample-support holders or cups 38 are mounted on the rod so that samples to be levitated may be placed on each holder before the rod 36 is placed in the tube 12. When in place, the rod and holders 38 support the samples to be levitated in a position substantially in line with the longitudinal axis of the tube 12. The rod 36 and the holders 38 are preferably composed of a dielectric material such as quartz.

OPERATION

After being weighed and cleaned, the several samples 40, 42, and 44 are each placed on the spaced holders 38 as shown in the drawings. The rod 36 is then placed within the tube 12 and the upper end is closed in a vacuum-tight manner by the adaptor joint 20. The valves 26 and 28 are then opened and the system is evacuated to a pressure of the order of from about 10^{-6} to 10^{-8} torr.

A coolant (such as water) is passed through the coil 22 and an RF power generator for the coil 22 is actuated. As shown in FIG. 2, the electromagnetic field from the coil lifts the sample 42 from its position on the holder 38 into a position of support-free suspension between the upper end lower coil portions 30 and 32 where the sample 42 is heated and melted in the electromagnetic field generated by the coil. During its period of being molten, the sample 42 is continuously stirred by the RF field because of the circulating (eddy) currents in the sample. Due to the viscosity of the liquid metal as well as the RF field, the molten metal assumes a spherical configuration. The continuous stirring of the metal in the molten state causes a rapid release of the contained gas in the sample. The released gas is extracted by the use of any one of various types of pumps such as a diffusion pump, and turbo-molecular pump. The quantity of gas extracted is measured and analyzed by the use of a mass spectrometer or other means such as chemical, chromatographic, fractionation techniques followed by pressure measurements in calibrated volumes to obtain the analysis of the extracted gas.

After the gas is extracted from the sample the valve 26 is closed in order to isolate the extracted gas from the tube 12 and, more particularly the molten sample, which when cooled, could reabsorb some of the extracted gas. The coil is then deenergized and the molten sample drops into the holder 38 where it solidifies. The tube 12 is then translated by lowering through the coil in order to bring the next sample 44 into the RF field for levitation, melting, and extraction of the gas.

The foregoing procedure is useful for actual gas analysis. However, the system may also be used for quality control of gas in metals. Isolation of the extracted gas may not be required and the mass spectrometer may be replaced by a simple pressure measuring device such as thermocouple 46 communicating with the tube portion 14 by a conduit 48. Thus a measure of the gas content of the metal as required in manufacturing can be determined by the included simple pressure measuring instrument 46 such as a thermistor. The volume of the quartz tube 12 and the connecting tube portion 14 are minimized to a volume of the order of, say, 50 to 100 cc. by closing the valve 26. During levitation melting of typical metals weighing 0.5 gram a pressure of the range of

from 10^{-3} torr to 1 torr of gas pressure would be developed in this small volume.

In addition, the system is suitable for isotopic dilution analysis for the elements carbon, oxygen, nitrogen, and hydrogen. For that purpose, known quantities of high purity isotopes of C¹³, O¹⁸, N¹⁵, and D would be added to the system prior to levitation of each sample. The ratio of C¹²/C¹³, O¹⁶/O¹⁸, N¹⁴/N¹⁵, and H/D in the extracted gas provides the necessary information for directly calculating the quantities of each of these elements in the original metal sample.

The following example illustrates the practice of the invention:

EXAMPLE

The samples of approximately 0.5 gram of copper were prepared by abrading the sample surfaces with a file and cleaning in benzene followed by acetone. The samples were placed in the system which was then evacuated to a pressure of the order of 10^{-6} torr. A prepared mixture of He and D₂ was introduced at a pressure of approximately 1 torr, and valve 26 was closed. The samples were levitated at room temperature and then heated to approximately 11-1200° C. for 2 minutes. The resulting gas mixtures were then extracted for each sample into evacuated 3 liter volumes associated with the inlet system of the mass spectrometer by opening valve 26.

Immediately on transfer of the gas and closing of valve 26, the generator was deenergized and the molten sample dropped to the holder where it solidified. It was found that once the quartz tube had been conditioned by pre-baking at 600° C. in vacuum, it could be reused after short term exposures to air or chemical cleaning without requiring further long term baking.

A typical mass spectrometer gas analyses obtained after levitation melting copper samples in a D₂ and He mixture are shown in the table. The starting sample mixture consisted of 20.75% D₂ and 79.25% He. Sample No. 2 was typical of the gas analyses obtained after levitation of high purity vacuum arc melted copper in the gas mixture from which the hydrocarbon content of the sample is calculated. An advantage of this technique is that the sample is available for reanalysis.

TABLE.—GAS ANALYSIS

Sample	H ₂	HD	D ₂	He	CO	CO
No. 1 Mixture			20.75	79.25		
No. 2 0.5 gm. Cu	0.61	1.29	19.10	77.67	0.91	0.42

Although the system has been described for multiple sample analysis, it is readily useable for analysis of a single sample with or without the sample holder 36 in the tube 12. Without the holder a single sample is supported on the bottom of the tube.

Accordingly, the device of the present invention provides a metal levitation gas extraction system which overcomes the disadvantages of prior levitation devices in that the levitation chamber is minimized to exclude the

levitation coils and associated metal parts and to include only the sample or samples to be analyzed. Moreover, the device of the present invention provides for the analysis of one or more samples for a given setup for extracting and analyzing the gas from metal samples.

It is understood that the above specification and drawings are exemplary of technically and economically feasible apparatus and methods for extracting and analyzing gases from metal samples.

What is claimed is:

1. Apparatus for analyzing gas extracted from an electrically conductive material by levitation melting in a controlled atmosphere, comprising walls forming a sealed melting chamber for at least one sample of the material, the walls being composed of a dielectric material, means wholly external of the walls for establishing in the chamber an electromagnetic field for levitating and melting the material sample, and means communicating with the melting chamber for withdrawing and analyzing the gas evolved from the sample, whereby no extraneous members are present in the electromagnetic field and within the melting chamber to evolve gas and contaminate the gas evolved from the sample under analysis.
2. The apparatus of claim 1 wherein the melting chamber is devoid of electrically conductive material.
3. The apparatus of claim 1 wherein the walls forming the melting chamber comprises a tubular member having a vertical longitudinal axis.
4. The apparatus of claim 3 wherein the means for establishing an electromagnetic field includes a pair of vertically spaced induction coil means for inducing the field in a vertical zone substantially coaxial with the tubular member.
5. The apparatus of claim 3 wherein an elongated sample support member is disposed within the tubular member and has a plurality of sample holders disposed along the length thereof, which sample holders are spaced by a distance greater than the high intensity zone of the field.
6. The apparatus of claim 3 wherein one of the electromagnetic field means and the tubular member are vertically movable with respect to the other.
